UNITED STATES PATENT OFFICE.

HERMAN C. SAGEHORN, OF CHICAGO, ILLINOIS, ASSIGNOR OF ONE-HALF TO
FRED G. ROEMPLER, OF CHICAGO, ILLINOIS.

ELEVATOR.

No. 843,302.

Specification of Letters Patent.

Patented Feb. 5, 1907.

Application filed May 18, 1906. Serial No. 317,505.

To all whom it may concern:

Be it known that I, HERMAN C. SAGEHORN, a citizen of the United States, residing at Chicago, in the county of Cook and State of Illinois, have invented a new and useful Improvement in Elevators, of which the following is a specification.

My invention relates to means for preventing the operation of the cars or cages of elevators while a door of the elevator-shaft is open; and the present invention constitutes a modification of the invention set forth and generically claimed in my pending application, Serial No. 317,504, of even date here-
15 with.

My present invention is illustrated in its preferred embodiment in the accompanying drawings, in which—

Figure 1 represents a vertical sectional view of an elevator shaft and cage equipped with my improved device; Fig. 2, a broken plan section taken as indicated at line 2 of Fig. 1; Fig. 3, a broken vertical section taken as indicated at line 3 of Fig. 2; Fig. 4, a similar view showing the elevator-door partly open; Fig. 5, a broken plan section with the floor of the elevator-cage indicated in dotted lines; and Fig. 6, a broken vertical section taken as indicated at line 6 of Fig. 3.

30 In the construction illustrated, A represents an elevator-shaft equipped with a series of doors A' (one shown); B, a vertically-movable car or cage; B', a cable passing through the elevator-cage and serving to control the operation thereof in a well-known manner; C, a locking device for the cable, having a member C' projecting in front of the elevator-cage; C², a locking device connected with the elevator-shaft at the plane 35 of the floor and coacting with the member C'; and C³, a cam connected with the inner surface of the base of the elevator-door and serving to operate the device C².

The elevator shaft and cage may be of any approved construction. I have shown a beam a at the plane of the floor a', said beam forming a part of the elevator-shaft. The beam is surmounted by a track or guide a² for the base of the door.

50 The device C comprises, in addition to the member C', which constitutes a lever pivoted on a bracket c beneath the floor of the elevator-cage, a link c', joining the inner end of the lever C' to a lever c², pivotally supported

on a bracket c³, carried beneath the floor of the elevator-cage, and a link c⁴, connected with the pivot c⁵ of the lever C' and having pin-and-slot connection c⁶ with the rear end of the lever c². The rear end of the lever C' is provided with a cable-gripping member c⁷, 60 and the member c⁴ is provided adjacent thereto with a cable-gripping member c⁸. A spring c⁹ serves normally to hold the gripping members separated and the lever C' in the position shown in full lines in Fig. 5. 65 When the lever C' is moved to the dotted position shown in Fig. 5, the cable will be gripped between the members c⁷ c⁸, thereby preventing starting of the car.

The mechanism C² comprises lazy-tong 70 levers c¹⁰, joined by a pair of links c¹¹ to a horizontally-shiftable locking-bar c¹² and by a pair of links c¹³ to a horizontally-movable bar c¹⁴; a bracket c¹⁵, connected with the beam a, upon which the lazy-tong levers are 75 supported by a pivot c¹⁶; a pair of links c¹⁷, connected with the lazy-tong levers and joined by a pivot c¹⁸ to link c¹⁹, the pivot c¹⁸ having connection with a guide c²⁰, attached to the beam a; a lever c²¹, joined by a pivot 80 c²² to a bracket c²³, carried by the beam a; a link c²⁴, connecting the lever c²¹ with a bell-crank lever c²⁵, joined by pivot c²⁶ to the beam a, and a link c²⁷, joining one arm of the bell-crank c²⁵ to one arm of a bell-crank lever c²⁸, 85 supported on a pivot c²⁹, carried by the beam a. The bell-crank c²⁸ has an arm c³⁰, equipped with a roller c³¹, connected with the cam C³. The link c¹³ extends loosely through slots c³², with which the projecting flange of 90 the locking-bar c¹² is provided. The lower ends of the locking-bars c¹² c¹⁴ are supported on a horizontal guide c³³. The levers c²¹ c²⁵ are provided with a series of perforations 95 whereby the throw of the locking-bars c¹² c¹⁴ may be regulated. The cam C³ comprises a horizontal slotted portion c³⁴, extending substantially across the base of the door, and an offset portion c³⁵ near the rear edge of the door. The arrangement is such that the 100 lever c²⁸ will be actuated to shift the bars c¹² c¹⁴ in the initial movement of opening the door and will also be actuated to retract said bars in the final movement of closing the door.

105 It will be understood that the mechanism C² is duplicated at each floor, so that all of the doors of the elevator-shaft are equipped

- with the protecting device. When the elevator-cage is stopped in the proper position and a door to the elevator-shaft thrown open, the cam connected with the door serves 5 through the medium of the lever c^{28} and the link-and-lever mechanism connected therewith to move the locking-bar C' to the position indicated in dotted lines in Fig. 5, thereby causing the members $c^7 c^8$ to grip the cable. This movement occurs in the initial 10 movement of opening the door, and the parts remain in the locking position while the door is being fully opened and until the door is returned to the fully-closed position, when the 15 roller c^{31} again enters the offset c^{35} of the cam and retracts the bar c^{12} . When the door is fully closed and the locking-grip upon the controlling-cable is released, the cable may be moved to start the car. It may be added 20 that, if desired, the bar c^{14} and the links c^{13} may be dispensed with in the present construction. They are duplicates of certain parts employed in the device, as shown in the above-mentioned application, and are not 25 necessary to the operation of the device herein shown.
- The construction has been described for clearness of understanding, and no undue limitation is to be understood therefrom.
- 30 What I regard as new, and desire to secure by Letters Patent, is—
1. The combination with an elevator-shaft,

a door therefor, an elevator-cage, and a cable controlling the movements of the cage, of cable-gripping levers supported beneath the 35 floor of the cage and having a projecting actuating member, a horizontally-shiftable member connected with the elevator-shaft and serving to actuate said projecting member, mechanism serving to actuate said horizontally-shiftable member, and a cam connected with the base of the elevator-door and serving to actuate said horizontally-shiftable member through the medium of said mechanism.

2. The combination with an elevator-shaft, a door therefor, an elevator-cage, and a cable controlling the movements of said cage, of a cable-gripping device having a pair of cable-gripping levers carried beneath the 50 floor of the cage and having also an actuating member projecting forwardly from the cage, a shiftable member connected with the elevator-shaft beneath said door and serving to actuate said actuating member, a horizontal 55 cam connected with the base of the door and having an offset portion, and a lever connected with said shiftable member and actuated by said cam.

HERMAN C. SAGEHORN.
